(57) **CLAIM**

The ornamental design for a dustcap for optical adapter, as shown and described.

DESCRIPTION

FIG. 1 is a front elevational view of a dustcap for optical adapter showing our new design;

FIG. 2 is a rear elevational view thereof;

FIG. 3 is a right side elevational view thereof;

FIG. 4 is a top plan view thereof;

FIG. 5 is a perspective view thereof;

FIG. 6 is a sectional view taken along the line 6-6 of FIG. 1;

FIG. 7 is a perspective view thereof shown in its environment of use;

FIG. 8 is a right side elevational view thereof shown in its environment of use; and,

FIG. 9 is a sectional view thereof shown in its environment of use.

The broken line portion of the figure drawings is included to show environment and forms no part of the claimed design.
